J. JACOBY.

MASSAGING APPARATUS.

APPLICATION FILED FEB. 8, 1916.

1,191,701.

Patented July 18, 1916.

Fig. 4.

UNITED STATES PATENT OFFICE.

JOHN JACOBY, OF LOS ANGELES, CALIFORNIA.

MASSAGING APPARATUS.

1,191,701.

Specification of Letters Patent. Patented July 18, 1916.

Application filed February 8, 1916. Serial No. 77,025.

To all whom it may concern:

Be it known that I, JOHN JACOBY, a citizen of the United States, and a resident of Los Angeles, in the county of Los Angeles and State of California, have invented a certain new and useful Improvement in Massaging Apparatus, of which the following is a specification.

One of the principal objects of my invention 10 contemplates the provision of an improved massaging apparatus, particularly adaptable for use in connection with a shower bath, by means of which the back and shoulders of the bather may be conveniently and thoroughly massaged and scrubbed without the necessity of the bather straining or twisting his arms, a disadvantage accruing to the use of the ordinary hand brush usually employed for this purpose, whereby elderly and rheumatic persons may find convenience in bathing.

A further object of my invention is to provide an improved apparatus of the class described which will be extremely simple, durable, efficient in operation, and inexpensive to manufacture.

With these and other objects in view which will become apparent as the description proceeds, the invention resides in the 30 construction, combination, and arrangement of parts hereinafter more fully described and claimed, and illustrated in the accompanying drawing, in which like characters of reference indicate like parts throughout the several figures, of which—

Figure 1 represents a view in side elevation of a massaging apparatus constructed according to my invention. Fig. 2 represents a front elevational view thereof. Fig. 40 3 represents a view in section taken horizontally and transversely on the plane indicated by the line 3—3 of Fig. 1. Fig. 4 represents a view in section taken horizontally on the plane indicated by the line 45 4—4 of Fig. 2.

Having particular reference to the drawing, it will be noted that the device may be used with convenience in connection with a bath tub. The tub is indicated generally at 50 5, and the faucet through which hot and cold water controlled by valves may pass, is indicated at 6. The faucet 6 is connected by means of a hose 7 with a nipple 8 carried at the lower end of a bored standard 9. A spray 10 is supported on a pipe 11 connected with the upper end of the standard.

Thus, by regulating the valves, the desired quantity and temperature of water may emerge through the shower head or spray 10. The nipple 8 is formed on an elbow, 60 one arm of which is connected to a horizontal pipe length 12. This pipe length is connected by means of an elbow 13 with an upright 14 carried by a suitable base 15 secured to the floor adjacent the end of the 65 tub. A brace 16 connected at its upper end with the standard 9 and at its lower end with the pipe length 12, maintains the standard rigidly in upright position.

This standard 9 is of a dove-tailed shape 70 in cross-section, throughout its entire length, and arranged for vertical reciprocation upon the standard is a plate 17 having marginal rearwardly extending flanges 18 along its lateral edges, which converge and slidably engage the sides of the standard 9. A socket 19 formed on the plate 17, receives a threaded shank 20 carried on a plate 21, to which latter a brush 22 of suitable type is secured. This brush may be formed of 80 ordinary hair bristles, or may be made of rubber or other material. The plate 17 at its lower end is equipped with a depending arm 23 to which is pivoted by means of a pin 24, the upper end of a link 25. 85 The lower end of this link is pivotally connected as at 26, with the inner end of a lever 27. The inner end of this lever is offset toward the standard to allow of the link 25 lying in a vertical plane. The lever 90 adjacent its central portion is pivotally mounted upon a pin 28 carried at the outer end of an arm 29, which arm is formed integrally with, or otherwise suitably connected to, a plate 30 having standard 95 engaging flanges 31 which snugly fit against the sides of the standard. A set screw 32 carried by one of the flanges, serves as means whereby the plate 30 may be maintained in adjusted position upon the standard. The outer end of the lever 27 is equipped with a suitable forwardly extending handle 33 whereby the lever may be readily manipulated.

The operation of the device is apparent 105 from the foregoing description, it being understood that the bather may, while standing under the shower with his back to the brush, manipulate the lever 27 so as to rock it up and down, thus moving the brush, 110 through the medium of the mechanism connecting the same with the lever, in a verti-

cally reciprocal path, whereby to thoroughly massage and scrub the back and shoulders of the bather. By adjusting the plate 30 vertically with respect to the standard, the 5 brush may be adjusted to the desired height. The device will be found to be of great convenience to elderly people and those suffering from rheumatism or other ailments which render the unusual strain and twisting 10 of the arms and trunk of a person using the ordinary hand brush, uncomfortable or painful.

Although I have described the preferred embodiment of my invention, I may desire 15 to make such changes in the construction, combination, and arrangement of parts thereof, as do not depart from the spirit of the invention and the scope of the appended claims.

20 I claim:—

1. The combination of a bath fixture having a faucet, of a standard having a bore extending therethrough, connecting means between the faucet and standard whereby 25 water may be directed through the latter, a shower head carried at the upper end of the standard, an upright arranged adjacent the bath fixture and having a base for supporting the upright, a horizontal member connecting the upright and standard, a brace 30 connecting said horizontal member and standard for maintaining the latter in a rigidly vertical position, a plate slidably vertically upon the standard, a brush detachably carried by the plate, said plate being provided with a depending arm, a second plate arranged upon the standard below the first and having means for retaining the second plate in adjusted positions upon the 35 standard, an arm carried by the second plate extending to one side of the standard, a lever pivotally mounted on said arm, a link pivotally connecting the inner end of the lever with the depending arm carried by 40 the first plate, and a handle carried by said lever whereby the latter may be oscillated for imparting reciprocal motion to the brush.

2. The combination with a bath fixture including a faucet, of a standard having a bore extending therethrough, connecting means between the faucet and standard whereby water may be directed through the latter, a shower head carried by the standard 50 at the upper end of the latter, means for supporting the standard in vertical position above the bath fixture, a plate slidably mounted for vertical movement upon the standard, a brush carried by said plate, a second plate mounted adjustably on the standard below the first plate and being provided with means for maintaining said second plate in adjusted position upon the 55

standard, an arm carried by the second plate extending to one side of the standard, a lever 65 pivotally mounted upon said arm, a link connecting the lever at one end with the first plate, and a handle carried by the lever whereby the latter may be oscillated to impart reciprocating motion to the brush. 70

3. The combination with a bath fixture, of a standard arranged thereabove, said standard being provided with a bore, connecting means between the faucet of the fixture and the standard whereby water may be directed through the latter, a shower head carried by the standard for directing water upon a person standing adjacent the standard, a plate slidably mounted on the standard and being provided with a brush, and means extending laterally of the standard 80 whereby the plate may be conveniently reciprocated upon the standard by a person standing adjacent thereto, and either facing the brush or having his back directed 85 thereto.

4. A device of the class described including a vertical standard having a bore extending therethrough whereby water may be directed through the standard, a shower attachment carried at the upper end of the standard, means for supporting the standard, a brush, means for mounting the brush whereby the latter may be reciprocated upon the standard, and means extending laterally 90 of the standard whereby the brush may be manually operated by a person standing under the shower head and either facing or standing with his back to the brush. 95

5. A device of the class described including a standard, means for supporting the same in a vertical position, a plate mounted for reciprocation on the standard and being provided with a brush, a second plate slidably mounted on the standard below the first and being provided with means whereby said second plate may be maintained in adjusted position upon the standard, a lever connected with the second plate and being provided with a handle, and a link connecting the lever with the first plate whereby the brush may be operated as the lever is oscillated. 100

6. A device of the class described including a standard, means for supporting the same in vertical position, a plate mounted for reciprocation on the standard and provided with a massaging element, a second plate slidably mounted on the standard and provided with means whereby the second plate may be maintained in adjusted position on the standard, and means mounted on the second plate and connected with the first, whereby the first plate may be reciprocated. 115 120

JOHN JACOBY.
